Term of patent 7 years

(Cl. D3—11)

FIG. 1

To all whom it may concern:

Be it known that I, Helen H. Kumme, a citizen of the United States, residing at Pelham, New York, have invented a new, original, and ornamental Design for a Glove or Similar Article, of which the following is a specification, reference being had to the accompanying drawing, forming a part thereof.

In the drawing:

Fig. 1 is a rear view of a glove, showing my new design; and

Fig. 2 is a side elevation thereof.

The essential features of my design reside in the portions shown in solid lines on the drawing.

I claim:

The ornamental design for a glove or similar article, as shown and described.
